SMOKING PIPE

Application filed January 29, 1927. Serial No. 164,487.

This invention relates to smokers' articles, such as pipes, and more particularly to an arrangement in such articles for cooling and purifying the smoke produced by burning 5 tobacco therein, prior to the inhalation of said smoke by the smoker.

In tobacco pipes of conventional construction, the smoke is delivered to the smoker at a relatively high temperature and with 10 its full content of undesirable and injurious substances, such as nicotine, etc. An object of the present invention, therefore, is the provision of means in said smokers' articles for causing the smoke to traverse a somewhat 15 longer passage than in usual practice, on its way from the pipe bowl to the smoker's mouth, cooling the smoke while traversing said passage, and purifying the smoke by the elimination of its injurious elements, which 20 elements when inhaled produce deleterious effects upon the smoker's physical and mental condition.

This object is accomplished by providing in the pipe a reservoir or chamber adjacent 25 to the passages conveying the smoke from the pipe bowl to the smoker's mouth, in which reservoir is confined a cooling medium, preferably water, (and for convenience of expression, the term water will be used herein- 30 after illustrative of any suitable cooling medium) so that the smoke, from the time it is produced in the smoke bowl to the time of its inhalation by the smoker, continually gives off its heat to the water, and reaches 35 the mouth of the smoker in a relatively cool condition, pleasant and comfortable for inhalation. If desired, instead of providing a reservoir with smoke passages thereabout or otherwise adjacent thereto, as above de- 40 scribed, the arrangement may be reversed so that the smoke passage is in the center and is surrounded by a water jacket, which is an equally desirable and efficient means for bringing about cooling of the smoke during 45 its passage through the smoke passages.

Simultaneous with the cooling of the smoke in the manner above described, substantial purification of the smoke is brought about to rid said smoke of its injurious sub- 50 stances. This is accomplished in my inven-

tion by interposing in the path of the smoke passages, preferably directly over the open end of the water reservoir and over the open ends of the smoke passages, a disk adapted to act as a baffle, so that the smoke in passing from the bowl to the stem of the pipe and before reaching the smoker's mouth may impinge upon said disk, and the injurious substances contained in the smoke may be condensed and deposited thereon, and prevented 55 from entering the smoker's mouth along with the smoke. The deposits of nicotine, etc., accumulating on the baffle drip into the reservoir or water jacket, where they collect and may be removed in the periodical cleaning 60 of the pipe. Thus, the water reservoir or jacket, whichever construction is used, in addition to performing its function of cooling the smoke, also acts as a collecting chamber for the sediment and injurious substances 65 dripped from the baffle, as above described. 70

The action of the baffle during smoking is automatic. By having the walls of the open end of the reservoir raised slightly above the open ends of the smoke passages, the baffle 75 normally rests on said raised reservoir walls, closing the reservoir. The smoke passages, however, remain open at all times. When the smoker produces a suction in the stem in order to draw in the smoke, the baffle, 80 which is of a material of very light weight, is raised off the mouth of the water reservoir and stays raised so long as the suction continues. When the smoker stops drawing in smoke, the baffle drops back on its seat and 85 closes the water reservoir. Thus, when smoke is not being drawn through the smoke passages, the baffle is seated and the water reservoir is closed, and every time the smoker takes a puff, the baffle is raised and unseated, 90 so that the undesirable and injurious substances in the smoke which impinge upon said baffle may be deposited thereon and may readily drop into the mouth of the reservoir. The baffle is, therefore, automatically opened 95 whenever required. The continual upward and downward oscillation of the baffle during smoking assists in causing the matter accumulating on the baffle to merge into drops and drip into the water reservoir. 100

While this invention will be pointed out more particularly in the appended claims, the invention itself, both as to its further objects and features, will be better understood from the following detailed description when read in connection with the accompanying drawing, in which Figs. 1 and 2 are cross-sectional views of two forms of tobacco pipes embodying my invention, showing one form of disk baffle, and Fig. 3 is a fragmentary cross-sectional view, similar to Fig. 1, showing a modified form of baffle.

Reference character 10 designates the pipe shank, which may be of any desired shape, and has formed therein a water reservoir or chamber 12, having the walls of its open end 13 raised slightly above the open end 10' of shank 10. Closely adjacent to said reservoir and extending substantially parallel therewith are smoke passages 14, which begin at the open end 10' of shank 10 and empty into the socket 18 formed in the lower portion or base 20 of shank 10. Although two such smoke passages 14 are shown, any desired number may be used and arranged to surround the reservoir 12, or, if desired, one smoke passage may be centrally disposed within the shank 10 with a water jacket surrounding it.

The bowl 22, for receiving the tobacco 23 to be burned therein, has a threaded stud 24 on the underside of said bowl, adapted to be received in the socket 18 of shank 10. A plurality of apertures 26, extending in various directions, are formed through the bottom of bowl 22 and stud 24, and empty into the socket 18.

The stem or mouthpiece 28 is enlarged at one end 30 and provided with internal screw-threads, so that the stem 28 may be connected with the open end 10' of shank 10, which is provided with external screw-threads 32 to engage the screw-threads of said mouthpiece. The other end of the stem 28 is provided with a tip 34 adapted to be received and held in the mouth of the smoker. The stem 28 is provided with a central bore or smoke passage 36, extending from the tip 34 to the chamber 38, which chamber is formed in the enlarged portion 30 of stem 28 when said stem 28 is screwed on the shank 10.

The smoke purifying means preferably comprise a flat circular disk or baffle 40 loosely disposed in chamber 38 directly over the open ends 14' of smoke passages 14, and seated on the raised wall portion 13 of reservoir 12.

To prevent the water 42 in reservoir 12 from being spilled when the pipe is not being used and is being carried in the pocket, or when the pipe is otherwise overturned, means are provided for closing the mouth of reservoir 12 at such times. This is accomplished by forming an annular shoulder 44 around chamber 38, so that when the stem 28 is given

an additional twist about the shank 10, the annular shoulder 44 presses the baffle 40 down over the mouth of water reservoir 12, causing the baffle to tightly seal said reservoir against leakage. When it is again desired to use the pipe for smoking, the stem 28 is given a twist in the opposite direction, freeing baffle 40 and permitting it to oscillate up and down during smoking, as above described.

When the smoker takes a puff on his pipe, the smoke traverses the following path: from bowl 22 the smoke passes through apertures 26 into socket 18, thence through smoke passages 14, impinging upon the underside of baffle 40 (which is unseated so that the reservoir 12 is open, as shown in dotted lines in Fig. 1), leaving on the underside of said baffle 40 any sediment or liquid substances contained in said smoke, and thence the smoke, now cooled and substantially purified, enters chamber 38 and passes into the mouth of the smoker through bore 36 of stem 28.

The baffles shown in Figs. 1 and 2 are free to oscillate during smoking, as described above. Fig. 3 shows a stationary form of baffle 46, which has a stud 48 adapted to be screwed into the open end of stem 28, said stud 48 having a bore 50 forming a continuation of stem bore 36. A plurality of apertures 52 are provided in the sides of stud 48, communicating with chamber 38, so that the smoke emptying into chamber 38 from smoke passages 14 may pass through said apertures 52 into bore 36 and thence into the smoker's mouth. A downwardly extending vane 54 is provided on the underside of baffle 46, so that the matter deposited thereon is guided into the open mouth of reservoir 12 and can easily drop off said vane 54 into said reservoir. A rubber washer 55 is provided on the underside of baffle 46 to facilitate tight sealing of the reservoir 12 against leakage when the pipe is not being used. The sealing of the reservoir 12 against leakage with this form of baffle is, however, substantially the same as the sealing with the form of baffle 46 travels with the stem 28.

The pipe shown in Fig. 2 is substantially the same as the one in Fig. 1, except that the shank 56 and reservoir 58 are of arcuate form, instead of straight form as in Fig. 1.

The advantages of the present invention are obvious. The pipe is easy to clean, needs little attention beyond filling the reservoir occasionally with fresh water and the usual periodical cleaning, and enables the smoker to enjoy a cool and pleasant smoke without the inhalation of poisonous and injurious substances, such as nicotine, etc.

The features of the present invention may be incorporated in any smoker's article in which tobacco is burned for the purpose of inhalation, and particularly in pipes of any shapes or dimensions. It is to be understood

that the embodiments shown herein are merely for the purpose of illustration and for affording an understanding of the invention and not for limitation thereof, and changes and modifications may be resorted to without departing from the spirit or scope of the invention.

I claim:

1. In a tobacco pipe having a smoke passage, a water reservoir in close proximity to and separated from said smoke passage for cooling the smoke on its travel to the smoker's mouth, and a baffle for trapping the nicotine and other impurities contained in the smoke and diverting them into said water reservoir before the smoke enters the smoker's mouth, said baffle being directly interposed in said smoke passage so that the smoke squarely impinges thereon.

2. In a tobacco pipe having a smoke passage, a water chamber in close proximity to said smoke passage and separated from said smoke passage for cooling the smoke while traversing said smoke passage, and means interposed directly in the path of said smoke passage for substantially purifying and ridding the smoke of its injurious constituents before said smoke reaches the mouth of the smoker, said means transmitting said injurious constituents to said water chamber.

3. In a tobacco pipe having a plurality of smoke passages, the combination of a bowl, a shank, a stem, a cylindrical water reservoir in said shank running substantially parallel with said smoke passages and being separated therefrom, said smoke passages extending through said shank and connecting the bowl with the stem, and vibratory means interposed in said smoke passages for trapping nicotine and other foreign substances and for depositing them in said water reservoir.

4. A tobacco pipe having a plurality of smoke passages comprising a shank open at one end and having a bowl attached to the other end, a cylindrical water reservoir in said shank with its open end extending slightly beyond the open end of the shank, a stem having an enlarged end adapted to be attached to the open end of said shank, a chamber in the enlarged end of said stem adjacent the open end of said shank, said smoke passages being provided in said shank around said reservoir and running substantially parallel therewith, said passages beginning at the bowl and emptying into said stem chamber, and a baffling member screw-threaded into said stem chamber and positioned directly over the open end of the reservoir, thereby causing the smoke entering the stem chamber from the smoke passages to impinge upon said baffling member before being drawn into the smoker's mouth, said baffling member being adapted to close the open end of the reservoir to prevent leakage therefrom, when the stem is further screwed on the shank.

5. A tobacco pipe comprising an elongated reservoir separated from the smoke passage by a thin wall and containing a liquid for cooling purposes, and a vibratory element interposed in the path of the said smoke passage for trapping nicotine and for ridding the smoke of its foreign substances, said vibratory element transmitting said nicotine and said foreign substances to said reservoir.

6. A tobacco pipe having a plurality of smoke passages, comprising a shank open at one end and having a bowl attached to the other end, a cylindrical water reservoir in said shank with its open end extending slightly beyond the open end of the shank, a stem having an enlarged end adapted to be screw-threaded on the open end of said shank, a chamber in the enlarged end of said stem adjacent the open end of said shank, said smoke passages being provided in said shank around said reservoir and running substantially parallel therewith, said passages beginning at the bowl and emptying into said stem chamber, and a baffling member screw-threaded into said stem chamber and positioned directly over the open end of the reservoir, thereby causing the smoke entering the stem chamber from the smoke passages to impinge upon said baffling member before being drawn into the smoker's mouth, said baffling member being adapted to close the open end of the reservoir to prevent leakage therefrom, when the stem is further screwed on the shank.

7. A tobacco pipe comprising a reservoir containing a cooling medium and a disk resting on said reservoir and extending into the path of the smoke passage so that the fluent smoke may deposit its liquid and solid constituents thereon, said disk being moved back and forth in the reservoir.

8. A tobacco pipe comprising a reservoir containing a cooling medium and a disk resting on said reservoir and extending into the path of the smoke passage so that the fluent smoke may deposit its liquid and solid constituents thereon, said disk being moved back and forth in the reservoir.

and forth during the smoking process and enabling the liquid and solid constituents deposited thereon to be cast into said reservoir.

5. In testimony whereof, I have signed my name to this specification this twenty-sixth day of January, 1927.

SAMUEL H. PARSON.
